DETACHABLE HOLDER FOR A FISHING ROD AND REEL FOR MOUNTING ON A HORIZONTAL RAIL

Basil D. Ingram, 222 N. Belcher Road,
Clearwater, Fla. 33515

Filed May 9, 1973, Ser. No. 358,660

Term of patent 14 years

Int. Cl. D22—05

U.S. Cl. D22—22

FIG. 1

FIG. 3

FIG. 4

FIG. 5

FIG. 1 is a side elevation of the detachable holder for a fishing rod and reel for mounting on a horizontal rail, showing my new design.

FIG. 2 is a top plan view thereof.

FIG. 3 is a front elevation thereof.

FIG. 4 is a rear elevation thereof.

FIG. 5 is a bottom plan view thereof.

I claim:

The ornamental design for a detachable holder for a fishing rod and reel for mounting on a horizontal rail, as shown.
